The ornamental design for a case for a remotely controlled toy vehicle, as shown and described.

DESCRIPTION

FIG. 1 is a top plan view of a case for a remotely controlled toy vehicle in accordance with my new design;

FIG. 2 is a front elevation view thereof;

FIG. 3 is a bottom plan view thereof;

FIG. 4 is a rear elevation view thereof;

FIG. 5 is a left side elevational view thereof;

FIG. 6 is a right side elevational view thereof;

FIG. 7 is a perspective exploded view thereof from the front and right sides showing three parts of the case: outer cap, inner cap and container; and,

FIG. 8 is a right side elevational view thereof with the outer cap thereof removed to reveal the inner cap thereof in the form of a hand control unit of the toy vehicle.

The broken line showing of the toy vehicle support plate is for illustrative purpose only and forms no part of the claimed design.
